UNITED STATES PATENT OFFICE.

HENRY G. STUTE AND BENJAMIN H. WALThER, OF EVANSVILLE, INDIANA.

COOKING RANGE.

Application filed April 27, 1923. Serial No. 635,041.

To all whom it may concern:

Be it known that we, HENRY G. STUTE and BENJAMIN H. WALThER, citizens of the United States, residing at Evansville, in the 5 county of Vanderburg and State of Indiana, have invented certain new and useful Improvements in Cooking Ranges, of which the following is a specification.

This invention relates to cooking ranges, 10 more particularly to devices of this character employing illuminating gas, gasoline, kerosene or other forms of hydrocarbons, and has for one of its objects to provide a device of this character, capable of being located against two faces of a structure, for 15 instance around one corner of a chimney breast or the like, to occupy less floor space, or occupying floor space otherwise not available.

20 In the kitchens of many houses, one or more of the walls are irregular or broken, for instance by a chimney breast or the like, thus producing waste spaces, and to utilize these hitherto waste spaces, is the principal 25 object of the present invention, which consists of constructing a cooking range capable of being located against two of the faces of the chimney breast or other irregular portion of the wall, and thus occupy hitherto unusable 30 floor space while retaining all the advantages of the ordinary range.

With these and other objects in view the invention consists in certain novel features of construction as hereinafter shown and 35 described and then specifically pointed out in the claims, and in the drawings illustrative of the preferred embodiment of the invention—

Figure 1 is a front elevation, and 40 Fig. 2 is an end elevation, of the improved device.

Fig. 3 is a plan view arranged against two faces of a structure such as a chimney, the latter being in transverse section.

45 Fig. 4 is a view similar to Fig. 3, arranged against two other faces of the chimney.

The improved device comprises a cooking range, for instance a gas range, and formed with a main body portion represented at 10. 50 This portion 10 comprises an elongated closed casing as shown having formed through its top apertures in which are placed lids 11. The front side of the casing has a series of apertures therethrough, through 55 each of which a lead-in pipe 12^a extends to

a burner (not shown) located within the casing beneath each plate. The outer end of the lead-in pipe terminates outside of the casing in the valve 12. A feed pipe 13 extends across the front of the casing to feed 60 fuel through the valves to the burners therein.

The back of the casing is extended upwardly to form the rear shield 14 which terminates along the upper edge in a forward extension to provide a warming shelf 15. Supports 16 are placed upon each end of the casing between the same and the underside of the shelf 15.

A base 17, supported upon legs 18, carries the substantially elongated casing thereon and in back of the casing 10 there is supported upon the base a pair of superposed ovens 19 and 20 having end doors 21 and 22. These ovens are, as shown, about half the 70 length of the casing 10 and one end of the casing is flush with the end of the oven, forming a substantially L-shaped structure, as is clearly shown in Figures 3 and 4. A frame 23 surrounds the ends of the ovens 80 and secures them to the casing 10 and shield 14. The lower oven is a broiling oven and the burner therefor (not shown) is supplied by a special valve 24 which as shown extends from the feed pipe 13 into the lead-in 85 24^a which extends into casing 10 as the other valves extend into lead-ins 12^a, thus placing all the controlling valves on the stove at the front and in a position where they are easily reached. The heat from the burner (not 90 shown) in the broiler oven which is supplied through valve 24 and lead-in 24^a also heats the upper oven 20.

As is shown these ovens are only half as long as the casing 10 thus giving the stove 95 a right angular formation. By enclosing the burners in the casing 10 the heat is retained and does not escape as in the open burner stoves. Thus after the casing becomes hot the burners can be turned down 100 and the heat retained beneath serves to continue the cooking process for a considerable length of time, thus greatly cutting down the consumption of fuel. When a direct flame is desired a lid may be removed from 105 over a burner, as in a coal range, and the utensil placed directly over the flame.

Owing to the contour of the structure embodying this invention, the same may be placed against a chimney as at 25, in such 110

a manner as to bear against two faces of the chimney thus making use of space which would ordinarily be useless.

The preferred embodiment of the invention is disclosed in the drawings and set forth in the specification, but it will be understood that modifications within the scope of the claims may be made in the construction without departing from the principle of the invention or sacrificing any of its advantages.

Having thus described the invention, what is claimed as new is:—

A range of the character described comprising, a base, means to provide a closed chamber of substantial length supported upon the said base and adapted to enclose

heating elements, said chamber having a plurality of openings through its top and further having a plurality of openings 20 through one side thereof to permit the passage of fuel conveyors thereinto, cover plates for said top openings, a pair of superposed ovens of less length than said casing supported upon said base behind the casing, said 25 ovens at one end being flush with one end of said casing, a fuel feed pipe extending across the front of said casing, and valve elements in said fuel pipe, for controlling the flow of fuel to said fuel conveyors.

In testimony whereof, we affix our signatures hereto.

HENRY G. STUTE.
BEN. H. WALTHER.
